UNITED STATES PATENT OFFICE.

EDGAR F. HATHAWAY, OF WELLESLEY, AND WALTER BIXBY, OF DORCHESTER, MASSACHUSETTS, ASSIGNORS TO SHAWMUT ENGINEERING COMPANY, OF DORCHESTER, MASSACHUSETTS, A CORPORATION OF MASSACHUSETTS.

MECHANISM FOR AND METHOD OF HANDLING YARNS OR THE LIKE.

Application filed May 31, 1924. Serial No. 716,881.

This invention relates to mechanism for and a method of handling yarns or the like, being especially useful in connection with the manufacture of carpets or rugs of the Axminster or similar types, such as produced on moquette or other pile fabric looms, and provides a method and a simple and effective mechanism for carrying out the same and whereby the yarn spacing and holding means may be applied to yarns or the like to maintain them in their established pattern or other arrangement upon a spool or other support until they are to be further manipulated. This application is a continuation as to certain common subject matter of our copending application, Serial No. 543,589, filed March 14, 1922, now Patent #1,512,928, dated October 28, 1924.

In the accompanying drawings disclosing one embodiment of our invention chosen for purposes of illustration and illustrating one manner of practicing our method,—

Fig. 1 is a plan view showing a portion of a spooling machine and related mechanism embodying one form of our invention, portions of the upper presser roll being broken away;

Fig. 2 is a front elevation of the mechanism shown in Fig. 1;

Fig. 3 is a vertical section through the mechanism shown in Fig. 2;

Fig. 4 is a detail view upon an enlarged scale.

Referring to the drawings we have illustrated one form of our invention as applied to a well known type of spooling machine such, for example, as that shown in the patent to Hathaway and Lea #1,152,380, it being understood that our invention is not limited to this or any particular construction of spooling machine nor in its broad aspects to a mechanical attachment to or associated with a spooling machine of any form or construction.

The illustrative form of spooling machine shown includes the side frame members 1, 1 and the cross support or member 2. Said side frame members carry suitable supports not necessary herein more fully to show or describe for rotatably mounting a spool 3 and one or more friction or presser rolls 4 for yieldably engaging the yarns as they are wound on to said spool. Said spool is adapt-

ed to receive winding movement in either direction at will or to be stopped, power being supplied in any suitable manner as by oppositely driven belts (not shown) which may be supplied respectively from the loose pulleys 5 or 6 to the fast pulley 7 (see Fig. 1). The spool 3 is preferably driven through suitable gearing or other connections from the driving shaft whereon said pulleys are mounted and operating the gear 3^a (Figs. 1 and 2) upon the spool shaft.

The yarn strands 8, or sets of strands if two or more be employed in a group, in the illustrated form of our invention, lead from the bobbin frame (not shown) on to said winding spool 3 passing over a guide bar 9 carried by brackets projecting outwardly and upwardly from the cross member 2, see Figs. 2 and 3. Intermediate said guide bar and the spool the yarns pass between the upper portions of the pins, pegs, teeth or the like 10 which, together with the cross bar or holder 11 in which they are supported in upright position, comprise the yarn guiding means or reed indicated generally at 12. The yarns preferably also pass over a second guide bar 13 similar to the guide bar 9 and also supported by brackets from the cross member 2. Thence the yarns lead on to the spool 3, being either overwound as shown in full lines in Fig. 3, or underwound, as indicated in dotted lines in said figure, as desired, or in accordance with the pattern requirements.

It will be observed that said pins, pegs or teeth of the reed are offset or deflected near their lower portions and in opposite directions upon the opposite side of the central peg or pegs of the reed. As best seen in Fig. 4, each peg with the exception of the central one, or a few at each side of such central peg, includes a straight upper portion 10^a, an inclined portion 10^b below the same, and a straight lower terminal or base portion 10^c (see Fig. 2) substantially parallel with but offset from the straight upper portion. Said pegs are offset by increments varying progressively from the center to the end of the reed. As herein shown, the offset of the pegs is outward toward the respective ends whereby a reed is provided having a wider bottom than top portion, but it will be understood that in certain instances, the

offset may be in the reverse direction, that is, inwardly from each end toward the center to provide a narrower bottom portion for the reed than its top portion.

The form of reed as shown is adapted for use where a series of yarns or the like is placed upon a support such as the winding spool herein shown, which support is of a different length than that of the yarn separator, comb or end-clamp which is to be positioned upon the yarn ends. In other words, the pitch of the yarns upon the spool is different from and herein less than the pitch between the yarn receiving portions of the separating device. Such difference in lengths between that of the yarn-holding space on the spool and in the separator or clamp is useful, for example, where a plurality of spools is to be placed serially end to end on a tube frame for use in "wide work." In such cases it will be understood that the spacing of the yarn tubes of the tube frame is uniform from end to end of the latter, whereas there is a gap or gaps between the yarn series of the several spools, due to the fact that the adjacent spool heads and pintles occupy a certain space. But by placing the yarn ends in a separator or clamp in which the interdental spaces are arranged to correspond with the spacing of the yarn tubes, in accordance with our invention, this difficulty is overcome, and the yarns may be properly presented and guided for passage through said tubes.

The separating device illustrated herein, best seen in detail in Fig. 4, comprises the separator, comb, spacer or holder 14, frequently termed a "yarn clamp" or "yarn end clamp" and also commonly known as a "transfer guide" or "aligning guide," preferably formed of sheet metal, and presenting a series of upright teeth 15 illustrated as of the barbed tooth type which will retain the yarns positioned between them, preventing any unintentional displacement of the yarns from the separator, spacer or holder in the direction lengthwise of the teeth and transversely of the yarns without the necessity of an additional cap or other yarn retainer. Said comb 14 is supported upon the machine in such relation to the yarns that after the latter have been wound upon the spool relative movement between the comb and the yarns, herein in a substantially vertical direction, will cause the latter to be placed between the teeth 15, as indicated in dotted lines at 8^a in Figs. 1 and 4.

Said comb as shown is positioned with its teeth upright, being seated in a suitable comb holder 17 rigidly connected to the reed holder 11 so that the comb and reed may be lifted together and relatively to the cross member 2 and the yarns whereby the latter are guided by the pegs and caused to pass precisely into the spaces between the teeth of the

comb. Said comb, clamp or separator, as illustrated, is positioned below the tuft yarns at the point where they leave the reed, and in such manner that when the yarns and comb are moved relatively the yarns are caused to 70 pass accurately into the comb, and herein at an angle past the barbs of the teeth 15. Accordingly said comb holder 17 is provided with a plurality of studs 18 which have a sliding fit each in a vertical slot 19 in said cross member 2 whereby a vertical movement 75 of the comb holder and reed in unison is permitted, to bring the comb into the desired relation to the yarns.

For raising said parts we have herein provided cam levers 21 each pivoted as at 22 upon the cross member 2 and interconnected by the link 23 to which is attached suitable operating means such as the transverse rods 24 each having a handle 25, said operating means being provided at either or both ends of the machine as desired. The lower face of the comb holder 17 rests upon said cam levers which when moved by either operating rod 24 will lift the comb holder and reed together into the dotted line positions indicated in Fig. 3 and in part in Fig. 2. Said comb holder and reed are held in said lifted position as by stop pins 26 upon the member 2 and against which the cam levers 21 rest just after passing their vertical position.

Shifting of an operating rod 24 by its handle in the opposite direction will restore the cam levers to their original or full line 190 position as shown in the figures, allowing the reed and comb holder 17 to drop by their own weight, or they may be moved down by the operative.

In operation the yarns are wound upon 105 the spool, passing through the top and herein in the narrow part of the reed in uniformly spaced relation, and extending in substantially straight lines onto the spool, as indicated by full lines in Fig. 1, so that there is 110 no danger of the yarns running off the edge of the spool during the winding operation. When sufficient yarn has been wound onto the spool and it is desired to apply the yarn separator or comb to maintain them in 115 proper relation, said comb and the reed are lifted, as by the means described, to the dotted line position of Figs. 3 and 4. Each strand or set of strands, if the latter are employed in sets of two or more, will first 120 have a relative movement between the straight upper portions of the teeth of the reed, will then be shifted to vary their pitch and to space them in conformity with the 125 yarn receiving portion or spaces between the teeth of the separator or comb and will then enter each a separate space or yarn-receiving portion in the latter, as indicated at 8^a by the dotted lines in Figs. 1 and 4. Said separator, comb or clamp having the yarn ends 130

in position therein may then be withdrawn from the holder and preferably will be attached to the spool by any suitable means.

In some instances it is desirable to cross-wind the yarns upon the spool. Preferably therefore we provide means for producing a relative reciprocation between the yarns and the spool in a direction axially of the latter during the winding of the yarns. In the present form of our invention we have shown the cross member 2 as having a slideable support in suitable bearings 30 upon the side frame members 1, 1. Said cross member 2, which herein carries the reed 12, the comb 14, and associated parts seen in Fig. 2, may thus be moved longitudinally and substantially horizontally thereby to reciprocate the yarns relatively to the spool to cause them to be wound upon the spool at an angle.

Any suitable mechanism may be employed for reciprocating said cross member 2, and we have herein shown for that purpose, referring to Figs. 1 and 2, a bevel pinion 31 fast upon the yarn spool shaft and meshing with a bevel gear 32 at the upper end of a substantially vertical shaft 33, see Fig. 2, supported in suitable bearings upon the machine frame. Said bevel pinion 31 and bevel gear 32 may be of any desired ratio but are represented as respectively 1 to 2 whereby one complete reciprocation will be imparted to the cross member 2 for each two turns of the spool.

At its opposite or lower end said vertical shaft 33 is operatively connected to a short horizontal shaft 34 through meshing bevel pinions 35. Said horizontal shaft is rotatably supported upon the machine frame and has fixed upon its forward end a crank plate 36 having upon its outer face a slot 37 in which is adjustably positioned a crank pin 38. Pivotedly supported upon said crank pin is one end of a link 39, the opposite end of which is pivoted as at 40 upon the cross member 2. Preferably a clutch 41 is provided having an operating member 42 and by means of which the crank plate and associated reciprocating mechanism may be thrown optionally into or out of operation.

When the cross winding mechanism is not to be employed the cross member 2 may be locked in normal position for straight winding by suitable mechanism, such as the latch 43, see Fig. 2, pivoted upon the machine frame and engageable with a notch in the periphery of the crank plate, in which position it is retained as by the spring 44. During operation of the cross winding mechanism said latch may be swung down and across center against the stop 45, in which position also it will be held by said spring.

It will be understood that any desired type of cross winding may be provided by vary-

ing the ratio between the speed of rotation of the spool and of the reciprocatory movement imparted to the cross member 2. By the mechanism shown the yarns will be wound in double looped form, somewhat in the manner of a figure 8. The extent of the reciprocation and consequently also the angle or extent of the cross winding may be regulated by adjusting the throw of the link 39, the crank pin 38 being shifted for this purpose in the slot 37 of the crank plate.

From the foregoing description it will be understood that our method of positioning a series of yarns or the like in a separator where such separating means is of a length different from that of the yarn support, and where therefore the pitch of the series of yarns differs from that of the yarn receiving portions of the separator, includes the steps of assembling the yarns in substantially parallel relation upon a suitable support such as a spool, whether straight or cross-wound thereon, or in providing such support or spool whereon the yarns have previously been positioned or wound, and subsequently varying the pitch of the yarns by shifting them laterally, outwardly or inwardly as the case may be, and in opposite directions from the central yarn or yarns of the series and by increments varying progressively from said center, and in finally positioning the yarns so shifted, and whose pitch has thus been made to conform to that of the yarn receiving portions of the separating means, in said separating means by relative movement between the same and the

yarns.

Our invention is not limited to the illustrative embodiment thereof herein disclosed.

We claim:

1. In combination, in mechanism for winding tuft yarn spools in carpet manufacture, a spool support, a reed through which the yarns are adapted to pass to said spool, a portable yarn separating member, means to support the latter in upright position adjacent the reed, and means to move said separating member and said reed in unison and relatively to the yarns to apply said separating member thereto, said reed, during said movement, acting to guide the yarns accurately for reception in said separating member.

2. Mechanism for handling yarns or the like comprising in combination means for supporting a series of yarns, a portable separator with which the yarns are adapted to be engaged to hold them spaced, said separator having yarn receiving portions spaced differently than said yarns on the supporting means, means relatively to move said yarns and separator toward each other to apply the separator to them, and means for shifting the yarns during said relative move-

ment of approach of the yarns and separator to space them in conformity with said yarn receiving portions of the separator.

3. Mechanism for handling yarns or the like comprising in combination means for supporting a series of yarns, a portable separator to be applied to the yarn ends, said separator having yarn receiving portions spaced differently than said yarns on the supporting means, means for guiding the yarns to space them in conformity with said yarn receiving portions of the separator, and means for effecting relative movement between said yarn guiding means and said separator on the one hand and said series of yarns on the other, thereby to position the yarns in said yarn receiving portions of the separator.

4. Mechanism for handling yarns or the like comprising in combination a spool whereon the yarns are wound, a spacer for the yarns having teeth of a pitch differing from that of the wound on yarns, a reed having deflected portions, and means for moving said yarn spacer and reed in unison to shift the yarn ends to conform their pitch to that of the yarn spacer and to apply the latter to the shifted yarn ends.

5. That method of preparing tuft yarn spools preliminary to the placing of the yarns in the receivers of a yarn carrier or tube frame which comprises winding the series of yarns on the spool, with a given pitch, in increasing the pitch of the yarn ends by shifting them outwardly from the center of the series and to progressively increasing extents, and in effecting the placing of the yarn ends so shifted in suitable yarn separating and holding means, whereby they are properly spaced for placing in the receivers of a yarn carrier or tube frame in which said receivers correspond in pitch to that of the shifted yarn ends.

6. That method of effecting the placing of separating means for a supported series of yarns or the like where the longitudinal extent of the separating means differs from the transverse extent of the yarn series which comprises assembling the yarns in substantially parallel relation and with a certain pitch between them, and in effecting the placing thereon of separating means for the individual yarns while varying the pitch of said yarns to conform to that of the separating means.

7. In mechanism for preparing tuft yarn spools in carpet manufacture for reception by the yarn carriers or tube frames, the combination with spool holding means, means for turning the spool to wind on the yarns and means to produce relative movement between the yarns and spool axially of the latter during the winding, of yarn guiding and separating means including a reed having teeth of a given spacing at one portion

of their lengths to guide the yarns during winding thereof and of a different spacing at another portion of their lengths and adapted for cooperation with the yarn ends to effect a spacing thereof differing from 70 that of the wound on yarns.

8. In mechanism for handling a series of yarns or the like, in combination with means for moving the yarns longitudinally, a reed having teeth spaced differently at different portions of their length, said teeth having one of their end portions of a given and substantially uniform spacing to guide the yarns during said longitudinal movement thereof, and being laterally offset or inclined 75 at their portions adjoining said end portions and to progressively varying extents lengthwise the reed, means to shift the reed longitudinally thereof to effect cross movement of the yarns during their longitudinal movement, and means to shift said reed in the direction of its teeth to bring said offset or inclined portions thereof between the yarns 80 thereby to vary the yarn spacing.

9. In mechanism for handling a series of yarns or the like, in combination with means for moving the yarns longitudinally, a reed having teeth spaced differently at different portions of their length, said teeth having one of their end portions of a given and substantially uniform spacing to guide the yarns during said longitudinal movement thereof, and being laterally offset or inclined 90 at their portions adjoining said end portions and to progressively varying extents lengthwise the reed, and means to shift said reed in the direction of its teeth to bring said offset or inclined portions thereof between the yarns 95 thereby to vary the yarn spacing.

10. In mechanism for handling a series of yarns or the like, in combination with means for moving the yarns longitudinally, a reed, a movable support therefor, means to move said support lengthwise the reed to effect cross-movement of the yarns, a portable yarn spacer on said support, and means to move said support in the direction of the reed teeth to guide the yarns into and position them in said yarn spacer.

11. Mechanism for handling yarns or the like comprising in combination a spool, means to turn the spool to wind on the yarns, a spacer for the yarns having teeth of a pitch differing from that of the wound on yarns, a reed having deflected portions, means to reciprocate said reed to produce cross-winding of the yarns, and means for moving said spacer and reed in unison to shift the yarn ends to conform their pitch to that of the spacer and to apply the latter to the shifted 115 yarn ends.

12. Mechanism for handling yarns or the like comprising in combination a spool, means to turn the spool to wind on the yarns, means to effect cross-winding of the yarns, 120

a spacer for the yarns having teeth of a pitch differing from that of the wound on yarns, a reed having deflected portions, and means for moving said spacer and reed in unison to shift the yarn ends to conform their pitch to that of the spacer and to apply the latter to the shifted yarn ends.

13. Pattern setting mechanism for the tuft yarn spools of moquette and like pile fabric looms comprising in combination a spool, means to turn the spool, a reed for guiding the yarns passing to the spool, means to effect relative reciprocatory movements between said reed and spool in a direction axially of the latter to produce cross-winding of the yarns, and mechanism for rendering said last named means optionally operative or inoperative and at the latter time for locking said reed and spool against said relative axial movement.

14. In yarn spooling mechanism for the tuft yarns of moquette or other pile fabric looms the combination of a spool, means to turn the same to wind on a series of yarns, guiding means to effect a given spacing of the yarn during winding, a yarn spacer of a length differing from that of the spool and having teeth correspondingly differently spaced from the spacing of the wound on yarns, and means for shifting the yarns to conform to the tooth spacing of said spacer.

15. In yarn spooling mechanism for the tuft yarns of moquette or other pile fabric looms the combination of a spool, means to turn the same to wind on a series of yarns, guiding means to effect a given spacing of the yarn during winding, a yarn spacer of a length differing from that of the spool and having teeth correspondingly differently spaced from the spacing of the wound on yarns, and means for shifting the yarns to conform to the tooth spacing of said spacer and for applying the separator to the yarns in a single operation.

16. In yarn spooling mechanism for the tuft yarns of moquette or other pile fabric looms, in combination, a spool, means to support said spool for rotation, a reed to guide and space the winding-on yarns, a yarn end holder, and means to move said reed and said holder relatively to the yarns to apply the holder thereto.

17. In yarn spooling mechanism for the tuft yarns of moquette or other pile fabric looms, in combination, a spool, means to sup-

port said spool for rotation, a reed to guide and space the winding-on yarns, means to reciprocate said reed longitudinally during the winding operation to effect cross-winding, a yarn end holder, and means to produce relative movement between said reed and said holder on the one hand and said yarns on the other to position the ends of the spooled yarns in said holder.

18. In a pattern setting frame, means for applying a yarn spacer to the yarns where the teeth of said spacer differ in pitch from that of the yarn on the spool, comprising, in combination with a spool support, a support for the spacer, a reed having its teeth spaced at one portion of their length to correspond with that of the yarn on the spool and deflected so as to correspond at another portion of their length with the pitch of the teeth of the yarn spacer, and means relatively to move said reed and said spacer on the one hand and the yarns on the other to apply the spacer to the yarns.

19. In a spooling machine for the tuft yarn spools of moquette or other pile fabric looms, means rotatably to support a spool to be wound, spool rotating mechanism, a reed for guiding the yarns onto the spool, automatic means to traverse said reed in opposite directions during the spooling operation to cross-wind the yarns, means to render said traversing means operative or inoperative at will, and locking means to hold said reed and spool against relative axial movement when said traversing means is rendered inoperative.

20. In a spooling machine for the tuft yarn spools of moquette or other pile fabric looms, means rotatably to support a spool to be wound, spool rotating mechanism, a reed for guiding the yarns onto the spool, a support for said reed reciprocable lengthwise the spool, and means to reciprocate said support during the spooling operation to cross-wind the yarns, said means including a crank, driving connections therefor, a link operatively connecting said crank and the reed support, and means for varying the crank throw to adjust the reciprocatory movement given the reed.

In testimony whereof, we have signed our names to this specification.

EDGAR F. HATHAWAY.
WALTER BIXBY.
